PICTURE TRANSMITTING SYSTEM

Alda V. Bedford, Collingswood, N. J., assignor,
by mesne assignments, to Radio Corporation of
America, New York, N. Y., a corporation of
Delaware

Application November 30, 1934, Serial No. 755,304
Renewed April 8, 1938

17 Claims. (Cl. 178—7.2)

My invention relates to picture transmitting systems and particularly to systems of the type employing a cathode-ray transmitter tube.

In a preferred type of cathode-ray transmitter tube, a mosaic of light-sensitive elements is positioned at an acute angle with respect to the axis of the tube whereby an optical image may be projected upon the same mosaic surface that is to be scanned by the electron beam. Because of this design, the electron beam scans a keystone shaped area on the mosaic, instead of a rectangular area, unless a correction is made in the horizontal deflection, with the result that the picture appearing at the receiver is distorted.

When employing the above-described type of tube, a correction must be made in the vertical deflection, also, to avoid a distorted picture at the receiver. This vertical correction, like the horizontal correction, is necessitated by the position of the mosaic with respect to the tube axis.

It is, accordingly, an object of my invention to provide a picture transmitting system of the above-mentioned type which will transmit an undistorted picture.

A further object of my invention is to provide an improved method of and means for correcting keystone error in a cathode-ray tube of the above-mentioned type.

A still further object of my invention is to provide means for correcting errors in the vertical deflection in a cathode-ray tube of the above-mentioned type.

Other objects, features and advantages of my invention will appear from the following description taken in connection with the accompanying drawings, in which

Figure 1 is a circuit diagram of a television transmitter embodying my invention,

Fig. 2 is a simplified plan view of the cathode-ray transmitter tube shown in Fig. 1,

Fig. 3 is a similar side view of the above-mentioned cathode-ray tube,

Fig. 4 is a circuit diagram showing a modification of a portion of the circuit shown in Fig. 1,

Figs. 5 to 10 are curves which are referred to in explaining the keystone correction feature of my invention, and

Figs. 11 and 12 are curves which are referred to in explaining the vertical deflection correcting feature of my invention.

Referring to Fig. 1, the television transmitter includes a cathode-ray transmitter tube 1 of the type which is described in an article by V. K. Zworykin, published in the January, 1934, issue of the Proceedings of the Institute of Radio Engineers. This tube includes an electron gun consisting of a cathode 3, a control electrode 5 and a first anode 7. A second anode 9 is provided which, in addition to accelerating the electrons, aids in the electrostatic focusing of the electron beam. The second anode also functions as a collector of photo-electrons which are emitted from a mosaic 11 of light-sensitive elements.

The light-sensitive elements of the mosaic 11 are insulated from each other and from a metallic back plate, as described in the above-mentioned publication.

An optical image of the object 13 to be transmitted is projected upon the mosaic 11 by means of a suitable optical system 15. In order that the light-sensitive surface of the mosaic 11 may have the optical image projected thereon and, at the same time, be scanned by the electron beam, it is positioned at an acute angle to the longitudinal axis of the cathode-ray tube. More specifically, it is positioned at an acute angle to the axis of the electron gun.

The cathode-ray tube 1 is provided with suitable deflecting devices, such as deflecting plates 17 and deflecting coils 19, for deflecting the electron beam both horizontally and vertically to scan the mosaic 11. If an optical image is projected upon the mosaic, picture signals are developed during the scanning of the mosaic by the electron beam, these picture signals appearing across a resistor 21 which is connected between the mosaic back plate and ground. These picture signals are supplied to a suitable transmitter 23 or to a transmission line for transmission to a receiver.

Because of the angular position of the mosaic 11 with respect to the electron gun, certain corrections must be made in both the horizontal and vertical deflection of the electron beam. That such corrections are necessary will be apparent by referring to Figs. 2 and 3, like parts in these figures and Fig. 1 being indicated by the same reference numerals. In Fig. 2 the dotted lines 25 indicate the limits of the horizontal deflection of the electron beam. It will be evident that when

the beam is striking the lower portion of the mosaic it traverses a shorter path thereon than it does when it is striking the upper edge of the mosaic, providing the angle between the limits of the horizontal deflection remains constant as the beam is deflected upwardly. As a result, the beam scans a keystone shaped area on the mosaic that is indicated by the area enclosed in dotted lines 27. One of the main objects of my invention is to so correct the horizontal deflection that a rectangular, rather than a keystone, shaped area is scanned on the mosaic.

In Fig. 3 the dotted lines indicate several positions of the electron beam as it is deflecting upwardly on the mosaic. From inspection of this diagram it will be apparent that, for a given angular upward deflection of the electron beam, it traverses a longer path on the mosaic at the top thereof than it does at the bottom. As a result, unless a suitable correction is made, the picture appearing at the receiver will be crowded together in the lower region of the picture.

Referring now to the deflecting circuits shown in Fig. 1, the vertical deflecting circuit for supplying a saw-tooth current to the deflecting coils 19 is indicated generally at 29, while the horizontal deflecting circuit for supplying a saw-tooth voltage to the deflecting plates 17 is indicated generally at 31.

Both deflecting circuits are controlled by an impulse generator 33 which generates horizontal deflecting impulses at a comparatively high frequency and vertical deflecting impulses at a comparatively low frequency. In the particular embodiment illustrated the horizontal deflecting impulses occur at the rate of 10,290 per second, while the vertical deflecting impulses occur at the rate of 60 per second. The impulse generator 33 may be of any suitable type, one form comprising a disc driven by a synchronous motor, the disc containing openings therein through which light is projected upon a photo-electric cell. An impulse generator of this type is shown in French Patent No. 742,671, dated January 4, 1933, and, as applied to interlaced scanning, in Ballard application Serial No. 623,325, filed July 19, 1932, and assigned to the Radio Corporation of America. While the frequencies of the deflecting impulses given above are for a system employing interlaced scanning, it will be understood that my invention is not limited to such a system.

The vertical deflecting circuit includes an amplifier tube 35, a discharge tube 37, and an output tube 39. The particular amplifier tube 35 illustrated is of the pentode type having a cathode 41, a control grid 43, a screen grid 45, a suppressor grid 47 and a plate 49. The control grid 43 is provided with a suitable bias potential by means of the usual self-bias resistor 51 which is shunted by a by-pass condenser 53. The screen grid 45 and plate 49 are supplied with positive potentials from a suitable unidirectional plate or "B" voltage supply (not shown) through filter resistors 55 and 57, respectively. Suitable by-pass or filter condensers 59 and 61 are provided in the screen grid and plate circuits.

The vertical deflecting impulses are impressed upon the input circuit of the amplifier tube 35 through a resistor 63 and a coupling condenser 65.

The output circuit of the amplifier tube is coupled by means of resistance coupling to the input circuit of the discharge tube 37. The discharge tube 37 may be of the three-element type, as illustrated, comprising a cathode 67, a control grid 69 and a plate 71. The grid leak resistor

70 has a resistance value which is high enough to bias the tube 37 substantially to cut-off during the intervals between impulses, said impulses causing the grid to collect electrons.

As is well known, in order to produce a flow of current through the deflecting coils 19 which has a good saw-tooth wave form, it is necessary that the voltage impressed across the coils contain a saw-tooth component in addition to the impulse component which would be required if the deflecting coil circuit were purely inductive. This saw-tooth component is provided by charging a condenser 73 from the plate voltage supply through a highly resistive circuit which includes a filter resistor 75, a variable resistor 77 and a fixed resistor 79. This charging circuit also includes another variable resistor 81, which has a comparatively low resistance value, for supplying the necessary voltage impulse component. The positive potential for the plate 71 of the discharge tube 37 is supplied through the filter resistor 75 and the resistors 77 and 79.

In operation, the vertical deflecting impulses which are supplied from the impulse generator 33 are given a negative polarity whereby they appear in the input circuit of the discharge tube 37 as impulses of positive polarity. The grid 69 of the discharge tube 37 normally is sufficiently negative to substantially block plate current flow between the deflecting impulses. The condenser 73, which will be referred to as the vertical saw-tooth condenser, is charged at a substantially constant rate through the high impedance circuit 75-77-79, whereby the voltage across the condenser 73 gradually increases in value. As soon as a positive impulse appears on the control grid 69, the discharge tube 37 becomes highly conductive, whereby the condenser 73 discharges very rapidly through the resistor 81 and the discharge tube. This discharge through the resistor 81 gives the desired impulse component to the voltage wave supplied to the input circuit of the tube 39. The charge and discharge of the condenser 73 produces a saw-tooth voltage wave thereacross.

The combined saw-tooth component and impulse component are impressed through a coupling condenser 83 and a resistor 85 upon the input electrodes of the tube 39.

The output tube 39 may be of the pentode type comprising a cathode 87, the control grid 89, a screen grid 91, a suppressor grid 93 and a plate 95. The tube is provided with the usual self-bias resistor 97 and by-pass condenser 99. The screen grid 91 is supplied with positive potential through a filter resistor 101, while the plate 95 is supplied with positive potential through a choke coil 103 and a resistor 105. The choke coil 103 is provided mainly for the purpose of maintaining the amplification at a proper level for high frequency components of the wave.

The input circuit of the output tube 39 includes a resistor 107 and a condenser 109 connected in series, the condenser 109 being shunted by a variable resistor 111. The purpose of the condenser 109 and variable resistor 107 is to control the wave shape of the current flowing through the vertical deflecting coils 19, whereby the above-mentioned correction may be made for the vertical deflection. This feature of the invention will be explained in detail hereinafter. The output circuit of the output tube 39 is coupled to the deflecting coils 19 through a suitable coupling condenser 113.

Referring now to the horizontal deflecting cir-

cuit 31, it includes an amplifier tube 115, a discharge tube 117, a second amplifier tube 119 and an output tube 121. The amplifier tube 115 may be of the pentode type comprising the usual cathode, control grid, screen grid, suppressor grid and plate. It is provided with a suitable negative bias by means of a self-biasing resistor 123. The plate is supplied with a positive potential through a conductor 125 and through a plate resistor 127.

10 The screen grid is supplied with positive potential through the conductor 125 and through a filter resistor 129, a "bleeder" resistor 128 being connected between the screen grid and ground.

15 The horizontal deflecting impulses are impressed upon the input circuit of the amplifier 115 through a resistor 131 and a coupling condenser 133. The amplified impulses are impressed through a coupling condenser 135 upon the input circuit of the discharge tube 117.

20 The discharge tube 117 is of the screen grid type, the tube illustrated being a pentode comprising a cathode 137, a control grid 139, a screen grid 141, a suppressor grid 143 and a plate 145. The tube 117 is biased at a suitable negative potential by means of a self-biasing resistor 147. The plate 145 is supplied with positive potential through the conductor 125, a filter resistor 149, a buffer resistor 151, and a plate resistor 153. It will be noted that the resistors 147 and 149 are provided with by-pass condensers.

25 The screen grid 141 is supplied with positive potential through the conductor 125 and through a resistor 155. The resistor 155, together with a resistor 157 connected between the screen grid 141 and ground, forms a potentiometer connected across the plate voltage supply for lowering the screen grid voltage to the desired value. The resistors 157 and 155 also function as a grid 30 leak resistor for the screen grid.

40 In addition to the steady voltages supplied to the plate and screen grid through the above-described circuits, saw-tooth voltages are impressed upon the plate 145 and the screen grid 141 through a circuit which will be described later.

45 In order to produce the saw-tooth voltage which is to be applied to the deflecting plates 17, a condenser 159 is provided which is charged through the three resistors 149, 151 and 153. The condenser 159 is discharged periodically through the discharge tube 117 to produce a saw-tooth voltage wave across the condenser 159 in the same manner as described in connection 50 with the vertical deflecting circuit.

55 The saw-tooth voltage is impressed through a coupling condenser 161 upon the input circuit of the amplifier tube 119. This tube may be of the pentode type, comprising the usual cathode, control grid, screen grid, suppressor grid, and plate. A positive potential is supplied to the screen grid through the conductor 125 and a filter resistor 163. A positive potential is supplied to the plate through the conductor 125, the filter resistor 163, a variable wave-shaping resistor 165, and a plate resistor 167.

60 In order to permit a control of the deflecting voltage wave shape, a condenser 169 is connected in series with the plate resistor 167 and ground whereby the amplitude of low frequencies is 65 exaggerated. The extent to which the lower frequencies are amplified more than the higher frequencies is determined by the extent to which signals are shunted around the condenser 169 by the variable resistor 165.

The amplified saw-tooth wave which appears across the resistor-condenser combination 161-169 is impressed upon the input circuit of the output tube 121. In the embodiment illustrated, the output tube 121 is of the three-electrode type comprising of a cathode 171, a control grid 173, and a plate 175. The input circuit of the tube 121 includes a resistor 177 and a resistor 179 to which the control grid 173 is connected through a variable tap for the purpose of controlling the amplitude of the deflecting voltage wave. The resistors 177 and 179 are shunted by a small capacity condenser 181 for the purpose of filtering out the highest frequencies in the saw-tooth wave which might produce undesired resonant effects in the transformers 183 and 185 which couple the deflecting plates 17 to the output circuit of the tube 121. It will be noted that the tube 121 is provided with the desired negative bias by means of a self-biasing resistor 187, while the plate potential is supplied through a filter resistor 189 and the primary of the output transformer 183. The output transformer couples the output circuit of the tube 121 to a cable, indicated by the dotted lines 191, which extends from the horizontal deflecting circuit to the cathode-ray tube 1. This transformer steps down the voltage to a value low enough to make the shunting effect of the distributed capacity of the cable negligible.

20 The auto-transformer 185, which is located in the immediate vicinity of the cathode-ray tube 1, is provided for stepping up the deflecting voltage to the high value required for deflecting the electron beam.

25 It will be noted that in the above-described circuits all filter resistors and self-bias resistors are provided with suitable by-pass condensers.

30 Referring to the keystone correcting portion of the circuit, it includes an amplifier tube 193 which may be of the pentode type as illustrated. The input circuit of the tube 193 is connected across the saw-tooth wave condenser 73 in the vertical deflecting circuit by means of a coupling condenser 195 and a connection through 35 ground.

35 A positive potential is supplied to the plate of the pentode 193 from the plate supply through the conductor 125 and resistors 197 and 199 which are connected in parallel. A resistor 201 is included in the circuit to lower the plate 40 voltage to the desired value. Resistors 197 and 199 are provided with a by-pass condenser 203.

45 It will be apparent that a substantially pure saw-tooth wave appears across the resistors 197 and 199 and that this wave is 180° out of phase with respect to the saw-tooth wave appearing across the condenser 73, the phase having been reversed by the amplifier tube 191. The saw-tooth wave appearing across the resistors 197 and 199 is shown in Figures 8 and 10.

50 In accordance with my invention, this saw-tooth wave is utilized for modulating the voltages applied to the plate 145 and screen grid 141 of the horizontal circuit discharge tube 117 where- 55 by the amplitude of the horizontal deflection is gradually decreased as the electron beam is deflected upwardly, the electron beam always being deflected substantially the same amount to the right as to the left of the center of the 60 mosaic.

55 In order to modulate the plate voltage, the point intermediate the two resistors 151 and 153 is connected through a coupling condenser 205 and a variable tap to a point on the resistor 197. 65

The plate modulation is produced by the flow of vertical saw-tooth current through the plate resistor 153 whereby a voltage corresponding to this current is added to the steady voltage provided by the plate supply.

The screen grid 141 of the discharge tube 117 is connected through a coupling condenser 201 to the plate end of the resistors 197 and 199 whereby a vertical saw-tooth voltage modulates the screen grid voltage due to the flow of vertical saw-tooth current through the screen grid resistor 157.

The relative values of the plate modulating voltage and the screen grid modulating voltage may be adjusted by means of the variable tap on the resistor 197. The values of both modulating voltages may be adjusted simultaneously after the desired balance has been obtained by adjusting the value of the resistor 199 which is made variable for this purpose. It will be seen that, as the electron beam is deflected upwardly, the keystone correcting circuit causes a gradual reduction in the voltages on the plate and screen grid of the discharge tube 117 since the vertical saw-tooth wave is decreasing in value as indicated in Fig. 8. The operation of the circuit will be better understood by referring to Figures 5 to 10.

In Fig. 5 there is shown a series of charging curves for the saw-tooth condenser 159 in the horizontal deflecting circuit. The upper curve 209 shows how the voltage increases across the condenser 159 as it is charged through the resistors 149, 151 and 153 with a certain voltage applied to the condenser-resistor combination. The lower curves 211, 213, 215 and 217 show how the voltage across the condenser 159 builds up for lower voltages applied to the same condenser-resistor circuit.

The curves in Fig. 6 show how the voltage across the condenser 159 varies as the said condenser discharges through the discharge tube 117 with different voltages applied to the discharge tube screen grid 141. The steepest discharge curve 219 represents the case where a comparatively high positive voltage is applied to the screen grid 141. The other curves 221, 223, 225 and 227 show how the condenser 159 discharges less rapidly as the positive voltage on the screen grid 141 is decreased.

Referring to Fig. 7, there are illustrated two saw-tooth curves. The upper curve 229 is the one which would be generated with the keystone correcting circuit omitted, that is, with no modulation on the plate and screen grid of the discharge tube 117. This curve has been constructed by means of the top curve 209 in Fig. 5 and the top curve 219 in Fig. 6. It will be seen that the condenser 159 charges gradually along the curve 209 during the time T_1 and discharges suddenly along the curve 219 during the time T_2 . It will be understood that during the time T_1 the discharge tube 117 is biased beyond cut-off, while during the time T_2 a positive synchronizing impulse is being impressed upon the control grid of the discharge tube 117 to render it highly conductive. Only a small number of horizontal saw-teeth for each vertical saw-tooth has been indicated in Figs. 7 and 8 in order to simplify the drawings.

If an attempt is made to gradually reduce the amplitude of the horizontal saw-tooth wave by modulating only the plate voltage of the discharge tube 117, the resulting saw-tooth has the appearance of the lower saw-tooth wave 231.

This saw-tooth wave has been constructed from the several curves in Fig. 5, since it is assumed that the charging voltage is being reduced gradually by the saw-tooth voltage indicated in Fig. 8, and from the top discharge curve 218 in Fig. 6. It has been assumed that the discharge rate of the condenser 159 has not changed, even though the plate voltage of the discharge tube 117 has been lowered, because, for all practical purposes, this is true for tubes of the screen grid type. Since the discharge rate has remained the same, the average value of the voltage across the condenser 159 has decreased in value as indicated by the saw-tooth curve. Obviously a saw-tooth wave of this character would produce a distorted picture. Specifically, it would produce a picture which would not have vertical sides.

If a three element vacuum tube were employed in place of the screen grid tube 117, the effect illustrated by the saw-tooth curve 231 would not be so pronounced since the discharge rate of the condenser 159 would change appreciably with a change in plate voltage. For this reason, by utilizing a triode discharge tube with modulation on its plate only, a keystone correction may be obtained which is appreciably better than no correction, but the correction will be imperfect.

Fig. 9 illustrates the keystone correction that is obtained by means of the circuit illustrated in Fig. 1. The saw-tooth curve 233 illustrated in this figure has been constructed by means of the charging curves shown in Fig. 5 and the discharge curves shown in Fig. 6, since the charging voltage and the screen grid voltage are being reduced gradually by the saw-tooth voltage indicated in Fig. 10. It is evident that by decreasing the discharge rate of the condenser 159 at the same time that its charging rate is decreased, it is possible to maintain the average voltage across said condenser substantially constant. In other words, the voltage level of the alternating current axis of the saw-tooth wave curve 233 is maintained constant. Considering the curves 231 and 233 in Figs. 7 and 9, respectively, from a slightly different viewpoint, the saw-tooth curve 231 is objectionable because it contains a strong vertical saw-tooth component whereas the saw-tooth curve 233 contains no such component. It has been found from experience that my improved keystone correcting circuit is reliable in operation and that it gives a practically perfect correction of the keystone effect.

Referring now to the previously mentioned correcting circuit for the vertical deflection error illustrated in Fig. 3, I correct for this error by causing the vertical deflecting saw-tooth wave to bend over as will be understood by referring to Fig. 11.

Referring to Fig. 11, if it were not for the fact that the mosaic 11 is at an angle with respect to the electron gun, for the vertical deflection, a perfect saw-tooth current wave would be desired as indicated at 235. As previously pointed out, however, it is desired to slow down the deflection of the electron beam as it is deflected upwardly. The saw-tooth may be "bent over" with a resulting slowing down of the electron beam by eliminating some of the low frequency components of the saw-tooth wave 235, the saw-tooth wave 235 being the one which appears across the saw-tooth condenser 13. In the vertical deflecting circuit illustrated in Fig. 1, the coupling condenser 113 and the by-pass con-

denser 99 are deliberately made small enough in capacity to eliminate enough low-frequencies for bending the saw-tooth curve over more than it is desired for the correction. The resulting saw-tooth curve is indicated at 237. The saw-tooth curve indicated at 239 is the one which is desired for obtaining a perfect vertical deflection correction. The saw-tooth wave is raised from the position of curve 237 to the position of curve 239 by means of the correcting circuit 107-109-111, previously described, which accentuates the lower frequencies. By varying the resistor 111, the vertical deflecting saw-tooth curve may be made to occupy almost any position between the two saw-tooth curves 237 and 235.

The curves in Fig. 11 represent both the flow of current through the vertical deflecting coils and the saw-tooth component of the voltage impressed upon the input electrodes of the amplifier. The wave shape of the voltage impressed upon the input electrodes of the amplifier 39 is indicated by the curve in Fig. 12. It will be seen that this voltage includes the necessary impulse component for producing the flow of saw-tooth current through deflecting coils.

In Fig. 4 there is illustrated another circuit for controlling the curvature of the vertical saw-tooth wave. Like parts in Figs. 1 and 4 are indicated by the same reference numerals. In the circuit of Fig. 4, the condenser 109 and resistors 107 and 111 of Fig. 1 have been replaced by a variable grid leak resistor 241. Also, the condensers 113 and 99 in the circuit have been given a capacity sufficient to pass the low frequency components of the saw-tooth wave efficiently. The curvature of the saw-tooth wave is controlled by adjusting the grid leak resistor 241 until the low frequency components are attenuated to the desired degree.

In some cases it may be preferred to deflect the electron beam from the edge of the mosaic farther from the electron gun to the edge of the mosaic nearer the gun, that is, from top to bottom in the cathode-ray tube illustrated. It will be apparent that, in such a case, the speed of vertical deflection should be increased as the beam approaches the bottom edge of the mosaic. This may be accomplished by so adjusting the grid leak resistor 111 of Fig. 1 that the saw-tooth wave bends upward above the line of a perfect saw-tooth, instead of downward.

Also, if the beam is deflected downwardly, the amplitude of the horizontal deflecting saw-tooth must be increased as the beam approaches the bottom edge of the mosaic, this being accomplished merely by applying a vertical deflecting saw-tooth wave to the discharge tube 117 which is 180 degrees out of phase to that assumed in describing Fig. 1. In other words, both the charging voltage and the positive screen grid voltage are increased as the beam is deflected downwardly. The change in amplitude of the charging voltage and in the amplitude of the positive screen grid voltage is always in the same sense, that is, the charging voltage and the screen grid voltage either increase together or decrease together.

From the foregoing description it will be seen that I have provided correcting circuits which enable an operator to so control the horizontal and vertical deflections of the transmitter tube electron beam that an undistorted picture is transmitted even though the transmitter tube mosaic is positioned at an angle with respect to the electron gun.

In the embodiment of my invention illustrated in Fig. 1, certain of the circuit values were as follows:

In the vertical deflecting circuit:

Resistor	70=4 megohms	5
Resistor	79=400,000 ohms	
Resistor	77=1 megohm	
Resistor	81=5,000 ohms	
Condenser	73=.5 micro-farads	10
Condenser	83=.02 micro-farads	
Resistor	85=.5 megohms	
Resistor	107=.5 megohms	
Resistor	111=.7 megohms	
Condenser	109=.01 micro-farads	

In the horizontal deflecting circuit:

Resistor	127=70,000 ohms	15
Resistor	129=4,000 ohms	
Resistor	128=20,000 ohms	
Resistor	153=200,000 ohms	20
Resistor	151=40,000 ohms	
Resistor	149=9,000 ohms	
Resistor	157=60,000 ohms	
Resistor	155=100,000 ohms	
Condenser	159=.0024 micro-farads	25
Resistor	167=2,000 ohms	
Resistor	165=2,000 ohms	
Resistor	163=2,000 ohms	
Condenser	169=.03 micro-farads	
Condenser	181=.0007 micro-farads	30
Transformer	183=5 to 1 step down ratio	
Transformer	185=15 to 1 step up ratio	

Other circuit values:

Resistor	201=1,000 ohms	35
Resistor	197=25,000 ohms	
Resistor	199=5,000 ohms	
Condenser	207=.4 micro-farads	
Condenser	205=.4 micro-farads	
Condenser	203=.01 micro-farads	40

It may be noted that the variable resistors are usually set at a value equal to about one-half the resistances values given for them in the above table.

It will be understood that various other modifications may be made in my invention without departing from the spirit and scope thereof and I desire, therefore, that only such limitations shall be placed thereon as are necessitated by the prior art and are set forth in the appended claims.

I claim as my invention:

1. In a cathode-ray tube deflecting circuit, means for producing a saw-tooth wave occurring at a relatively low frequency, means for gradually charging and suddenly discharging a condenser at a relatively high frequency to produce a saw-tooth wave occurring at said high frequency, and means for varying said charge and said discharge in accordance with said low frequency saw-tooth wave, said charge and discharge being so related that the average voltage across said condenser remains substantially constant.

2. In apparatus for producing a modulated saw-tooth wave, a condenser, means for charging said condenser at approximately a constant rate during a certain period, means for discharging said condenser suddenly at the end of said period, means for charging said condenser again at the end of said discharge period at a rate which differs from the preceding charging rate and which is approximately constant, and means for again suddenly discharging said condenser.

at a rate which differs from said preceding discharge rate by an amount such as to maintain the average voltage across said condenser substantially constant.

- 5 3. In combination, a cathode-ray tube comprising an electron gun and a mosaic of light-sensitive elements positioned in the path of the electron beam generated by said gun and also positioned at an acute angle to the axis of said gun, deflecting means for deflecting said electron beam vertically, deflecting means for deflecting said electron beam horizontally, means for producing a saw-tooth wave occurring at a relatively low frequency and for applying it to said first deflecting means, and means for producing a saw-tooth wave occurring at a relatively high frequency and for applying it to said second deflecting means, said last means comprising means for charging a condenser successively at a changing charging rate determined by said low frequency saw-tooth wave, an electric discharge tube of the screen grid type, and means for discharging said condenser successively through said screen grid tube at a changing discharging rate 25 determined by said low frequency saw-tooth wave.

4. In apparatus for producing a modulated saw-tooth wave, a condenser, a source of charging voltage and an impedance unit having a high resistance value connected in series with said condenser whereby the condenser charges at an approximately constant rate for a given value of said voltage, a screen grid tube having a control grid and a screen grid and having its cathode-anode space path connected across said condenser, means for maintaining said control grid at a negative potential whereby said condenser charges at said constant rate for a certain period, means for periodically decreasing said negative potential sufficiently for a certain period to cause said condenser to discharge suddenly through said tube, means for changing the positive potential on said screen grid for successive discharge periods, and means for changing the value of said charging voltage for successive charging periods, the changes in said charging potential and said screen grid voltage being in the same sense.

5. In combination, a condenser, means for charging said condenser successively at approximately a constant rate during charging periods, a vacuum tube having a plurality of control electrodes and having main electrodes connected across said condenser, means for periodically applying a potential to one of said electrodes such that said condenser discharges through said tube at the end of each charge period, means for changing said charging rate for successive charging periods, and means for applying a gradually changing potential to the other of said control electrodes whereby the discharge rate of said condenser changes for successive periods, the change in charging and discharging rates being in the same sense.

6. In combination, a cathode-ray tube comprising an electron gun and a mosaic of light-sensitive elements positioned in the path of the electron beam generated by said gun and also positioned at an acute angle to the axis of said gun, the top edge of said mosaic being a different distance from said gun than the bottom edge thereof, a vertical deflecting device for deflecting said beam vertically from near one of said edges to near the other of said edges, a horizontal deflecting device for deflecting said beam horizon-

tally, means for producing a saw-tooth wave occurring at a relatively low frequency and for applying it to said first deflecting means, and means for producing a saw-tooth wave occurring at a relatively high frequency and for applying it to said second deflecting means, said last means comprising a condenser, means for charging said condenser successively at approximately a constant rate during charging periods, a vacuum tube having a plurality of control electrodes and having main electrodes connected across said condenser, means for periodically applying a voltage impulse to one of said electrodes such that said condenser discharges through said tube at the end of each charge period, said voltage impulses occurring at said relatively high frequency, means for changing said charging rate for successive charging periods in accordance with said low frequency saw-tooth wave, and means for applying said low frequency saw-tooth wave to the other of said electrodes whereby the discharge rate of said condenser changes for successive periods, the change in charging and discharging rates being in the same sense.

7. Apparatus according to claim 6 characterized in that said vacuum tube is of the type in which the plate impedance remains substantially constant over a wide variation in potential applied between said main electrodes.

8. Apparatus according to claim 6 characterized in that said vacuum tube is of the screen grid type.

9. In combination, a cathode-ray tube comprising an electron gun and a screen structure positioned in the path of the electron beam generated by said gun and also positioned at an acute angle to the axis of said gun, deflecting means for deflecting said beam in a certain direction in the plane of said acute angle, deflecting means for deflecting said beam at right angles to said plane, means for applying a succession of saw-tooth deflecting waves to said first deflecting means, and means for so shaping each individual saw-tooth that said beam traverses the surface of said screen structure at a uniform speed in said certain direction as it is deflected.

10. In combination, a cathode-ray tube comprising an electron gun and a screen structure positioned in the path of the electron beam generated by said gun and also positioned at an acute angle to the axis of said gun, the top edge of said screen structure being farther from said gun than the bottom edge thereof, a deflecting device for deflecting said beam vertically from one of said edges to the other of said edges, means for applying a deflecting wave to said deflecting device, and means for so shaping said wave that said beam traverses a path on said screen structure in a vertical direction at a constant speed.

11. In combination, a cathode-ray tube comprising an electron gun and a screen structure positioned in the path of the electron beam generated by said gun and also positioned at an acute angle to the axis of said gun, the top edge of said screen structure being farther from said gun than the bottom edge thereof, a deflecting device for deflecting said beam vertically from said bottom edge to said top edge, means for applying a deflecting wave to said deflecting device, means for so shaping said wave that said beam is deflected at a decreasing speed as it approaches said top edge such that said screen structure is traversed in a vertical direction at a uniform speed, and means for simultaneously deflecting said beam in a horizontal direction.

12. In a television system, a cathode ray tube provided with screen structure and with means for developing a ray of electrons and directing the same at said structure, the axis of said ray developing means being inclined at an acute angle to said structure, means for causing the ray to scan said structure comprising a generator of a relatively low-frequency electrical wave and a generator of a relatively high-frequency electrical wave, an electron tube provided with a control grid and forming part of said second-named generator, a condenser and a source of charging voltage therefor forming part of said second-named generator, and connecting means between said generators for causing both the charging voltage and the bias on said control grid to vary in accordance with the low-frequency wave.
13. In combination, a cathode ray tube comprising an electron gun and a screen structure positioned in the path of the electron beam generated by said gun and also positioned at an acute angle to the axis of said gun, deflecting means for deflecting said beam in a certain direction in the plane of said acute angle, deflecting means for deflecting said beam at right angles to said plane, means for applying a succession of saw-tooth deflecting waves to said first deflecting means, and means for so shaping each individual saw-tooth that said beam traverses the surface of said screen structure at a uniform speed in said certain direction as it is deflected, said last means comprising a frequency selective means for causing the attenuation of low frequency components of said saw-tooth deflecting waves according to a certain law and another frequency selective means for causing the accentuation of low frequency components of said saw-tooth deflecting waves according to a different law than said certain law.
14. In combination, a cathode ray tube comprising an electron gun and screen structure positioned in the path of the electron beam generated by said gun and also positioned at an acute angle to the axis of said gun, deflecting means for deflecting said beam in a certain direction in the plane of said acute angle, deflecting means for deflecting said beam at right angles to said plane, means for applying a succession of saw-tooth deflecting waves to said first deflecting means, and means for so shaping each individual saw-tooth that said beam traverses the surface of said screen structure at a uniform speed in said certain direction as it is deflected, said last means including frequency selective means for attenuating low frequency components of said saw-tooth waves.
15. In combination, a cathode ray tube comprising an electron gun and a screen structure positioned in the path of the electron beam generated by said gun and also positioned at an acute angle to the axis of said gun, deflecting means for deflecting said beam in a certain direction in the plane of said acute angle, deflecting means for deflecting said beam at right angles to said plane, means including a coupling condenser in series in a transmission channel for applying a succession of saw-tooth deflecting waves to said first deflecting means, said coupling condenser having sufficiently small capacity to cause a substantial loss of low frequency components in said saw-tooth waves whereby each saw-tooth wave is caused to bend over, and means including said coupling condenser for so shaping each individual saw-tooth that said beam traverses the surface of said screen structure at a substantially uniform speed in said certain direction as it is deflected, said means also including a condenser in shunt to said channel, said shunt condenser having resistance effectively in series therewith and having resistance effectively in shunt thereto whereby certain low frequency components of said saw-tooth waves are accentuated.
16. In a cathode ray tube deflecting circuit, means for producing a saw-tooth wave occurring at a relatively low frequency, means for charging and discharging a condenser at a relatively high frequency to produce a saw-tooth wave occurring at said high frequency, and means for varying the rate of said charge and means for varying the rate of said discharge in accordance with said low frequency saw-tooth wave, said rate of charge and said rate of discharge being so related that the average voltage across said condenser remains substantially constant whereby the voltage level of the alternating current axis of said saw-tooth wave is constant.
17. In a cathode ray tube deflecting circuit, means for producing a saw-tooth wave occurring at a relatively low frequency, means for producing a succession of saw-tooth waves occurring at a relatively high frequency, and means for so modulating said high frequency waves by said low frequency wave that modulated high frequency waves are produced which contain substantially no low frequency saw-tooth component whereby the voltage level of the alternating current axis of said modulated high frequency waves is constant.

ALDA V. BEDFORD.
